FLUID FILTER OR THE LIKE

Nils O. Rosaen, Detroit, Mich., assignor to The Rosaen Filter Company, Hazel Park, Mich., a corporation of Michigan

Filed Mar. 13, 1961, Ser. No. 64,243

Term of patent 14 years

(Cl. D46—1)

FIG. 1 is a perspective view of the front and left side of a fluid filter, showing my new design;

FIG. 2 is a left side elevational view as observed from the left-hand end of FIG. 1;

FIG. 3 is a right side elevational view of the fluid filter as observed from the right-hand end of FIG. 1; and

FIG. 4 is a sectional view taken on the line 4—4 of FIG. 2.

The dominant features of my design reside in the portions shown in full lines.

I claim:

The ornamental design for a fluid filter or the like, as shown and described.
